UNITED STATES PATENT OFFICE.

JAMES E. DINGWALL AND WESTON D. PRUDDEN, OF DULUTH, MINNESOTA, ASSIGNEES
OF ONE-THIRD TO DONALD B. McDONALD, OF DULUTH, MINNESOTA.

FLAX-STRAW BEATING AND SCUTCHING MACHINE.

1,278,609.

Specification of Letters Patent. Patented Sept. 10, 1918.

Application filed October 22, 1917. Serial No. 197,980.

To all whom it may concern:

Be it known that we, JAMES E. DINGWALL and WESTON D. PRUDDEN, a subject of the King of England, and a citizen of the

United States, respectively, residing at Duluth, in the county of St. Louis and State of Minnesota, have invented certain new and useful Improvements in Flax-Straw Beating and Scutching Machines, of which the

following is a specification, reference being had therein to the accompanying drawing.

This invention relates to machines for treating flax straw and is particularly designed for the purpose of separating what is known as shives from the fiber of flax straw.

The principal object is to provide a machine of this character capable of producing clean smooth fiber from flax straw previously passed through a common threshing machine and not especially prepared for such treatment.

It is known in the art that flax may be grown and threshed with the special object in view of utilizing the straw for fiber and under such circumstances the straw is maintained in as uniform and straight condition as possible throughout its growing and threshing process. Straw thus produced is comparatively easy to handle in the further process of separating the shives from the fiber and machines for such purpose are common.

While our present machine, as above stated, is particularly designed for treating straw not thus especially grown and prepared, the same may prove efficient for such purpose and a further object is to produce an improved machine of this character which will more effectually perform its functions.

In the accompanying drawings forming part of this application and in which like reference characters indicate like parts:

Figure 1 is a side elevation of a flax straw treating machine embodying our invention,

Fig. 2 is a top plan view of same, and

Fig. 3 is a diagrammatic elevation of the straw engaging parts of the machine.

1 represents a suitable supporting frame upon which are rotatably mounted a plurality of straw engaging rollers, the straw being fed into the machine at one end and the

fiber discharged at the opposite end, the shives and other refuse being separated from the fiber during its passage through the machine.

In these respects the machine is very similar to others known in the art but we have introduced novel and individual characteristics of the rollers and other means for treating the straw while *en route* through the machine.

2 and 3 represent sections of a lighter superimposed fabricated supporting frame structure mounted upon the main frame 1, and 4 represents a still lighter and more open frame structure supported by the other mentioned frames.

At the feeding end of the machine is located a suitable feeding table 5 over which the straw is fed by hand to the first set of rollers 6-6 and 7-7 journaled in the intermediate supporting frame 2, the rollers 6-6 being below the rollers 7-7 and but slightly intermeshing therewith.

These rollers are externally fluted spirally having V-shaped corrugations about their entire outer surface and upon each pair horizontally, the spirality of the corrugations is opposite, the object being to exert an equal lateral stress in both directions upon the straw as it travels between the two sets of rollers. As before stated, these rolls slightly intermesh, that is to say the V-shaped projections on one roller extend slightly within the similarly shaped corrugations or depressions upon the other this being for the purpose of initially breaking the shives on the straw as it passes therebetween.

It is evident that a portion of the shives thus broken will be separated from the fiber and fall from the rolls 6-6 while the remainder of the straw passes on slightly upward and over a larger longitudinally fluted roller 8, the corrugations of which are similar in shape to those upon the previously described rollers except that they are somewhat closer together and extend parallel with the sides thereof. Above this roller 8

is reciprocally supported a series of vertically disposed swings or beaters 9 there being preferably six separate beaters in the series standing in close juxtaposition though not touching and the opposed faces of each

beater formed at an angle diagonally the axis of the roller.

Each beater is composed of a single piece of wood securely attached in any desired manner adjacent the free end of a corresponding horizontally disposed resilient supporting bar 10, the opposite end of which latter is fixed to the cross member 11 of the supporting frame 4.

10 Directly above each beater 9 and on top of the respective supporting bar is an expansive spiral spring 12 supported beneath the cross member 13 of the frame 4. These springs are for the purpose of accelerating 15 the downward motion of the beaters.

Upon the under side of the approximately extreme end of each bar 10 is rigidly disposed a depending bracket 14 carrying a suitable roller 15 for engagement with the 20 cam 16 mounted upon the cross shaft 17, there being one such cam for each beater, the action of which may be timed by their position radially upon the shaft 17 as is obvious. These cams are made to raise the 25 free ends of the bars 10 and their respective beaters by revolving the shaft 17 in an anti-clockwise direction, such motion being imparted by suitable belt and pulley attachment illustrated at 18 and by which the entire machine is operated.

When released from engagement with the cam, each beater will descend of its own weight assisted by its respective spring 12 upon the upper surface of the roller 8, the 35 lower ends of the beaters being concaved to coincide with the circumferential surface of the roller 8. This treatment is for the purpose of further breaking and dislodging the shives from the fiber and softening the latter. 40 A second roller 19 identical with the roller 8 and spaced but a short distance therefrom is also journaled upon the frame 1 and has a coöperating series of beaters 20 thereabove.

45 These beaters are fastened to supporting bars 21 attached to the cross member 22 of the frame 4 and each provided with an accelerating spiral spring 23 supported by the cross member 24.

50 The free ends of the supporting bars 21 rest upon the free ends of the like bars 10 they overlapping the latter considerably as illustrated at 25 and are raised by the action of the latter, thus requiring no special cam 55 engaging mechanism therefor.

The angle of the adjacent side walls of the beaters 20 is opposite to that of the beaters 9, this being for the purpose of counter-acting the lateral draft upon the 60 straw as it is engaged by the beaters.

During this beating process still more shives are separated from the fiber and the latter is further treated by passing intermediate of a pair of smaller fluted rollers 65 26 and 27, the corrugations thereupon being

V-shaped, parallel longitudinally the rollers and also slightly intermeshing as in the case of the rollers 6 and 7 before described.

From these rollers the straw passes under two similar rollers 28 and 29 placed one in 70 advance of the other and having a solid apron or plate 30 thereunder against which the straw is slightly impinged and further separated from the shives as it is moved along toward the large scutching roller 31. 75

The rollers 28 and 29 are revolved at different speeds, the latter at about thirty revolutions per minute and the former twenty-five, thus causing a slight stretching and straightening of the straw as it passes thereunder.

These rollers, as are the rollers 26, 27 and 31, are made of wood instead of metal, the object being to lessen the severity of action upon the fiber, and the rollers 28, 29 and 31 85 are the only ones which tend materially to draw out and straighten the fiber and remove the broken pieces of shives by drawing them longitudinally the fiber.

The straw, when leaving the roller 29, is 90 preferably on an upward inclination to a point approximately perpendicular with the outer edge of said roller and is there abruptly met by the descending radially spaced ribs 32 upon the circumferential surface of the roller 31 and which roller performs the final scutching and cleaning 95 process.

An arcuately shaped open mesh apron 33 is positioned below the roller 31 and in close proximity to the ribs 32. This roller is rotated at approximately 100 revolutions per minute and effectually concludes the separating operation, the separated pieces of shives being allowed to fall through the 100 perforated discharging table 34 and the apron 33.

A pulley 35 is mounted upon the end of the shaft 17 opposite to the driven end and from thence a suitable belt 36 conveys power to the pulley 37 on the shaft 38 upon which the roller or drum 31 is mounted. Upon the opposite end of the shaft 38 is a beveled gear 39 meshing with a like gear 40 on the roller driving shaft 41 mounted horizontally the 110 supporting frame 1 and adjacent the upper edge thereof. All of the rollers of the machine are driven either directly or indirectly from this shaft 41 and preferably by means of gearing substantially as illustrated, the rollers 7-7 and 27 being driven from their 115 lower coöperating rollers by suitable spur gears.

Having thus described our invention, what we claim as new and desire to secure by Letters Patent, is:

1. In a machine of the character described, a suitable supporting frame, coöperative breaking rollers at the receiving end of the machine, scutching and cleaning rollers at 130

the discharging end of the machine and rollers having reciprocal beaters co-operatively engageable with the circumferential surfaces thereof intermediate of the two first 5 mentioned groups of rollers.

2. A machine of the character described having a series of transverse rollers disposed longitudinally therein in the following relation, intermeshing breaking rollers, rollers having reciprocal beaters intermittently 10 striking same, cleaning and stretching rollers and a final scutching roller, substantially as described.

3. In a machine of the character described, the combination with a suitable 15 supporting frame, of slightly intermeshing corrugated breaking rollers, larger corrugated rollers having co-operative reciprocal beaters intermittently impinging same, 20 smaller corrugated cleaning and stretching rollers, and a scutching roller arranged respectively as enumerated.

4. The combination with a flax straw treating machine having a series of transverse rollers disposed longitudinally therein, of one or more corrugated rollers within the 25 series having co-operative reciprocal beaters mounted adjacent thereto and intermittently impinging same whereby the straw is 30 swunged between the roller and beaters during the process of its treatment in the machine.

5. The combination with a flax straw treating machine having a series of transverse rollers disposed longitudinally therein 35 of a pair of relatively large corrugated rollers approximately the center of the series of rollers, a series of vertically reciprocal beaters mounted above each large roller, a cam 40 shaft above and intermediate of said rollers

and means for imparting intermittent reciprocal motion from the cam shaft to the beaters substantially as described.

6. The combination with a flax straw treating machine having a series of transverse rollers disposed longitudinally therein, of a pair of relatively large corrugated rollers, a series of vertically reciprocal beaters mounted above each large roller and designed to strike same upon the limit of their 45 downward stroke, the adjacent side walls of the beaters being disposed in planes transverse the axis of the rollers, a cam shaft above and intermediate of the rollers and means intermediate of the cam shaft and the 50 beaters for imparting reciprocal motion thereto.

7. The combination with a suitable supporting frame having a feeding platform at one end and a discharging platform at the opposite end, of a series of cleaning and scutching rollers comprising two pairs of spirally corrugated slightly intermeshing breaking rollers adjacent the feeding platform, the spirality of the corrugations on each pair of 60 rollers being opposite to prevent abnormal lateral stress upon the straw as it passes therebetween, two larger rollers within the series, a series of vertically reciprocal beaters above each of said larger rollers, and means 65 for applying reciprocal motion to the beaters.

In testimony whereof we hereunto affix our signatures in the presence of two witnesses.
